JOSEPH J. DUFFY, OF BROOKLYN, NEW YORK, ASSIGNOR OF ONE-HALF TO GIDEON W. CARLETON, OF BROOKLYN, NEW YORK.

AERIAL TORPEDO.

1,221,426.

Specification of Letters Patent.

Patented Apr. 3, 1917.

Application filed April 8, 1916. Serial No. 89,756.

To all whom it may concern:

Be it known that I, JOSEPH J. DUFFY, a citizen of the United States, residing in the borough of Brooklyn, city of New York, in the county of Kings and State of New York, have invented certain new and useful Improvements in Aerial Torpedoes, of which the following is a specification, reference being had therein to the accompanying drawing.

My present invention refers to an aerial or high explosive or shrapnel shell having the functions and characteristics of a torpedo, the same being designed for use with airships of various kinds, particularly aeroplanes intended to ascend to a great height. The object of the invention is to provide an explosive weapon which can be released or dropped from any desired height above the ground or sea, and when it strikes a resisting surface, such as the earth or any object thereon, or the sea or any object thereon, the impact will instantaneously fire the explosive material with which the shell is charged and burst the same at a point above the surface of the earth or sea so as to spread destruction around the bursting point within a considerable radius, the bursting and the disastrous effects taking place therefore without the sinking of the torpedo into the ground or water, and hence being much more wide-spread and efficient because exerted over an area above the surface of impact; and the invention therefore comprises various details and peculiarities in the construction, arrangement, and combination of the various parts, substantially as will be hereinafter described and then pointed out in the ensuing clauses of the claim.

In the accompanying drawing illustrating my invention:

Figure 1 is a longitudinal section of my improved aerial torpedo shown as supported from the floor of an aeroplane;

Fig. 2 is an end view of the same;

Fig. 3 is an enlarged longitudinal sectional view of the means for exploding the torpedo;

Fig. 4 is a sectional view on the line 4, 4 of Fig. 3.

Similar characters of reference designate corresponding parts through the different figures of the drawing.

1 designates a pear-shaped, or other shaped, torpedo or bomb having a tubular axial extension 2 at its smaller end, which extension is provided with a number of lateral wings 4, four of them for example. The torpedo or shell 1 is filled with any preferred kind of high explosive and shrapnel, the explosive being contained within a central tube 3 mounted in a boss 32 at the larger end of the shell 1 and in an orifice 33 at the smaller end, in which orifice is also screwed the end 34 of the tubular member 2 which is in alinement with tube 3. This explosive material may be tri-nitro-toluol or any other high explosive suitable for a driving charge. The shrapnel or other material with which the shell is filled is disposed within the hollow interior 40 of casing 1 and around the explosive charge in tube 3.

When the shell is supported from an aeroplane or other aerial vehicle, it will preferably, for example, be hung from the flooring 5 of the plane or from any suitable part of an airship, balloon, or other device, its supporting position being preferably longitudinal as indicated in Fig. 1, and being close to and beneath the floor 5. The supporting means 80 may vary widely and consist of many different devices, but one which I find it convenient to employ comprises a vertical shaft 6 having thereon collars 8, 8, which collars are above and below the floor 5 and serve to retain the shaft 6 in its vertical position, the upper end of the shaft being provided with a lever 7 by means of which it can be turned in one direction or the other for the purpose of disengaging the lower end of said shaft 6 from its connection with the torpedo or shell. At the other end of the torpedo I use a similar vertical shaft 12 having collars 35 above and below the floor 5, the upper end of the shaft 12 being screw-threaded and provided with a nut 14 which screws down tightly

against the upper collar 35. This shaft 12 is simply an ordinary bolt of proper length and size, having at its lower end a head and engaging a yoke or hanger 13 in which is 5 hung a swinging pin 15 adapted to engage the inner bore of the tube 2 which is at the center of the wings 4, such engagement taking place when the shell is in its carried position shown in Fig. 1. It will be noted, 10 therefore, that as soon as the shell is released at its left hand end by the rotation of the shaft 6, it will fall into a vertical position, and then the tube 2 will slip off the pin 15 and the shell will be set entirely free to make 15 its descent.

The larger end of the pear-shaped shell 1 is furnished on the interior, as I have stated, with a boss 32, to which the tube 3 is connected, and this boss is internally screw-threaded, and into it is screwed the externally screw-threaded portion 10 of a projection or casting 9 which is hollow in its interior, having therein a vertical cylindrical recess, and said casting 9 is also provided 20 opposite to the projection 10 with another projection 11, the two projections 10 and 11 being each provided with a central bore which may be of the same or varying diameters, and one of which projections, as 25 10, is adapted to contain therein a detonating cap 22 by means of which the explosive charge in the tube 3 is ignited, while the other projection, as 11, is adapted to contain in its bore a sliding block or rod 16 having a 30 part 16^a of smaller diameter between which and block 16 is a shoulder bearing against the shaft 6 when the latter is in casting 9 as shown in Fig. 3, and said member 16^a having at its end a pin 17 of smaller diameter which 35 is adapted, when the rod 16 is properly actuated, to strike against the cap 22 and explode it. The rod 16 may project beyond the member 11, or may have any desired length. One way of arranging the same, 40 however, consists in providing the outer end of the rod 16 with an extension 26 of smaller diameter, to which is pinned a tube 27 of substantial length, perhaps of a length equal to the length of the torpedo or thereabout, 45 although it can be of any length, and the other end of which tube 27 is pinned or otherwise attached to the cylindrical part 30 of a block 31. The latter has also attached thereto a tube 29 of larger diameter 50 than the tube 27 and concentric therewith, which is sweated or otherwise fastened to another tube 28 also of larger diameter than the tube 27 but concentric therewith, said tube 28 being screwed into a threaded opening in the member 11 and against the shoulder on the rod 16. The tube 29 is of thin metal and will easily crumple up and collapse or break if given a sharp or a hard 55 blow, which will be the case if the devices 60 strike against an object when the shell falls, 65

for it will be seen that when the shell is released at its left hand end and allowed to drop into a vertical position, its descent will be in a vertical line for it will be guided by the wings 4, and the tubular members arranged as stated will project downwardly and being below the shell will be the first to strike against any object in their path, as for example, the surface of the ground or sea, the effect of which collision will be to cause 70 the inner tube 27 to propel the rod 16 and 16^a and the firing pin 17 through the casting 9 far enough to allow it to strike against the cap 22, and this will happen immediately upon the striking of the ground, it being obvious 75 that in this action the tubes 28 and 29 will either telescope each other should the fastening that unites them give way, or else collapse, while the tube 27 is acting on the firing pin. Instead of having the tube 27 connecting the parts 30 and 26, it is obvious 80 that the parts 30 and 26 may be made as a single long rod and the tube 27 omitted. It will be observed that the stem that carries the firing pin and extends beyond the 85 leading end of the torpedo, when constructed as described, is stiff and unyielding under ordinary conditions of handling the torpedo, and positively holds the firing pin from engagement with the detonating cap, but is 90 yieldable upon impact of the torpedo when the latter is discharged or falls. This adds an element of safety to the device which is maintained until the stem strikes, but which then yields, permitting detonation. 95

I have already referred to the casting 9 being provided with a vertical cylindrical cavity therein. When the shell or torpedo is supported in its inactive position, as shown in Fig. 1, this cavity will be occupied 1 by the lower end of the rod or shaft 6 which will engage the casting 9 so as to uphold the shell in such inactive position, but the parts can readily be released by laying hold of the handle 7. To this end the lower part of the 1 shaft 6 is provided with a vertical slot 18, communicating with which is a horizontal slot 20 which passes only part way around the circumference of the shaft 6 and leaves at the bottom an angular part 21, which, 1 when the shaft 6 is inserted in casting 9 and properly turned, will lie beneath the rod 16 or its reduced section 16^a, as shown in Fig. 4. That is to say, the end of the shaft 6 can be inserted in the casting 9, and the slot 18 1 will pass over the rod 16 and 16^a and the firing pin 17, then if the shaft 6 be rotated, the slot 20 will be caused to embrace the rod 16, thus placing the angular part or hook 21 beneath the rod 16 or 16^a so that when the parts are in this position, the shaft 6 is effectually hooked or locked to the casting 9 by being clutched to the rod 16^a and serves to uphold said casting 9 as well as to prevent the firing pin from being 1

5 moved against the cap should any agency accidentally strike against the parts that are connected with said firing pin, for any attempt to drive the firing pin into the cap would simply drive the shoulder at 16^a against shaft 6, as indicated in Fig. 3, and thus prevent pin 17 from moving. Furthermore, it should be noted that the inner cavity at the bottom of the shaft 6 at a point adjacent to slot 20, is provided with an annular groove 19 cut into the wall of the shaft 6 and passing either part or all the way around the interior of said recess, the same being designed to receive the end of the firing pin 17 as indicated clearly in Figs. 3 and 4. The wall of the shaft 6 in which is formed the groove 19 constitutes a safety shield that lies interposed between the firing pin and the detonator when the supporting shaft is moved into torpedo-supporting position.

In the boss or projection 10 is located, as I have already stated, the detonating cap 22 having a central member 23 in line with pin 17 and adapted to be struck thereby when there is no obstacle in the way, the result of which will be to explode the cap 36 and fire the explosive contents of the tube 24 forming a part of the cap so that the high explosive material in the tube 3 or elsewhere within the pear-shaped shell may be ignited and the whole device caused to burst with deadly effect. This detonator or cap may be constructed in many different ways, and I do not wish to be limited to what I have shown, as the same is given merely by way of example. In the same, however, is a pin 23 arranged to strike the mercury cap 36 and thereby explode the contents of the tube 24 and ignite the driving charge in the tube 3 so that the shell will be fired. I find it desirable to clothe the cap in felt, said felt being of a thickness of one-thirty-second of an inch preferably, as indicated, so as to prevent an explosion of the same which might occur from shock due to the outside of the shell being struck by bullets or other missiles fired thereat. This felt may be arranged in any desired way and cover the whole or a part of the cap.

It will be noted that the member 9 is made of tool steel or some equivalent substantial material so as to effectually protect the detonator and other parts from bullets or other projectiles, which, if fired against the same, might penetrate it and damage the whole structure or set off the interior charge prematurely. It will furthermore be noted that the annular groove which contains the end 60 of the firing pin 17 has a valuable function because it is possible that the aeroplane might be sailing about in such a way that the depending torpedo might strike against a tree or a house or other obstacle, the result 65 of which would be to break off the angular

part 21. If this is broken off and the pin 17 is in engagement with the annular groove, it will be evident that the shaft 6 cannot be disengaged from the torpedo without breaking off the firing pin 17, and when this is broken off the rod 16 and part 16^a would not have any effect in firing the torpedo, if the torpedo drops to the ground with the aeroplane at close quarters, and hence the annular groove prevents premature dangerous explosions of the torpedo under the circumstances specified. 75

Many changes in the precise construction and relative arrangement of the parts may be made without exceeding the scope of my invention, and I therefore reserve the liberty of making all such changes as may be necessary within the scope of the appended claims. 80

Having thus described my invention, what I claim as new and desire to secure by Letters Patent, is:—

1. An aerial torpedo, a projection secured to the leading end of the torpedo and extending forward therefrom, a detonator impact firing means for acting on the detonator, supported in the said projection and extending well in advance of the torpedo, and means for suspending the torpedo arranged to engage with the said projection and to be 90 interposed between the firing means and the detonator while the torpedo is suspended. 95

2. An aerial torpedo, a projection secured to the leading end of the torpedo, perforated longitudinally and formed with a recess intersecting the perforation, a detonator, an impact device supported by the said projection, extending forward therefrom and carrying a firing pin adapted to move through the longitudinal perforation in the said projection, and means for suspending the torpedo arranged to enter the recess in the projection and when therein to positively prevent the movement of the firing devices, the suspending devices being arranged when operated to disengage the said projection. 100

3. An aerial torpedo carrying a charge of explosive, a projection secured to the leading end of the torpedo, perforated longitudinally, a detonator supported in the inner end of the said projection, an impact device for firing the detonator, comprising a firing pin movable through the said perforation and a striking head at the forward end of the impact device, the impact device being relatively long whereby the striking head is a considerable distance in advance of the torpedo, and a collapsible tube connected at one end with the said projection and at the other with the striking head of the firing device arranged to hold the firing device rigidly in safety position under ordinary conditions of handling, but to collapse upon impact and permit the firing pin to act. 110

4. The combination with an aerial tor-

pedo comprising a detonator and an impact-operated firing pin, of manually controlled means for supporting the torpedo and arranged when moved into a certain position to release the torpedo and permit it to fall, the suspending means being provided with a safety shield adapted to be interposed be-

tween the detonator and the firing pin when moved into position to support the torpedo, the shield being formed with a groove in 10 which lies the end of the firing pin.

In testimony whereof I affix my signature.

JOSEPH J. DUFFY.
